UNITED STATES PATENT OFFICE

2,224,046

NUMBERING DEVICE

John Gorrell, Charleston, W. Va.

Application September 30, 1938, Serial No. 232,657

1 Claim. (Cl. 101—88)

My invention relates generally to type-high numbering devices, such as are commonly locked in the form with type and comprise a series of numbering wheels which are actuated in the operation of a press by a plunger and intermediary mechanism, and particularly to a device of this character in which the unit wheel is so arranged and constructed that its "0" symbol can be depressed, leaving the "No." in an operating position, together with means for holding the swinging pawl frame in a position to hold the "No." operating plunger in at a printing level and inwardly of an operating level, so that the device in the operation of the press will print the "No." without printing also the character on the unit wheel, thus enabling the pressman, at will, to print sheets containing only the symbol "No." without removing the numbering device from the form, which sheets so printed are then available for replacing spoiled sheets in the printing job.

Other important objects and advantages of my invention will be apparent from a reading of the following description taken in connection with the drawing, wherein for purposes of illustration I have shown a preferred embodiment of my invention:

In the drawing:

Figure 1 is a general top plan view of a substantially conventional numbering machine altered in accordance with the present invention.

Figure 2 is a top plan view of Figure 1.

Figure 3 is a transverse vertical sectional view taken through Figure 2 approximately on the line 4—4.

Figure 4 is a transverse vertical sectional view taken through Figure 2 approximately on the line 4—4 and looking toward the left in the direction of the arrows and showing the pawl frame free and the plunger fully extended in the operative position, in contrast to Figure 3 which shows the pawl frame held in "No." plunger retaining position.

Figure 5 is a transverse vertical sectional view taken through Figure 2 approximately on the line 5—5 and looking toward the left in the direction of the arrows.

Referring in detail to the drawing, the numeral 5 generally designates the numbering machine 50 which includes the main plunger 6 working in the end portion of the body 7, the main plunger having the character 8 on the upper end thereof for printing "No." on the work. The plunger 6 works through intermediary mechanism to 55 cause the pin 9 to work in the slot 10 of the cheek

piece 11 of the pawl frame which is pivoted on the shaft 12 which has a longitudinal notch 13 into which the depressible characters 14 on the respective unit wheel 15, tens wheel 16, hundredths wheel 17, thousandths wheel 18 and ten thousandths wheel 19, and any additional wheels that may be in the machine, move when manual pressure is exerted on the characters with the wheels in a position relative to the shaft 12 to permit the same to move into the notch 13, in a manner well known in the art. The cheek piece 11 has the tooth 20 thereon which in accordance with the present invention is adapted to be engaged in the notch 21 in the spring-pressed dog 22 which is pivoted as indicated by the numeral 23 to the body 7 in the position shown in Figures 3 and 4. A spring 24 mounted on a portion of the body 7 works against the outer side of the upper part of the dog 22 to hold the same in engagement with the tooth 20 as shown in Figure 20. In accordance with the present invention I mount on the top of the body portion containing the main plunger 6 a flat spring 25 which is held in place by a screw 26 at the outer end thereof and has a hole working on a small pin 27 on the inner end of the said body portion, the hole equipped end of the spring 25 being free to rise and fall when manual pressure is placed thereon. A finger 28 projects inwardly from the inner end of the spring 25 and the tip 29 on the upper end of the dog 22 is adapted to be engaged behind this finger by raising the inner end of the spring until the tip has cleared and reached the opposite side of the finger 28, when the spring is released so that the finger comes 35 to the inner side of the tip 29 and keeps the dog in the inoperative position illustrated in Figure 4, where the dog is out of engagement with the tooth 20 on the pawl cheek piece 11, and the main plunger 6 is in the fully extended position. 40 When the dog 22 is engaged with the tooth 20 on the cheek piece as indicated in Figure 3, the main plunger 6 has its character 8 at such an elevation as to print "No."

Between the cheek pieces 11 of the pawl is 45 carried the shaft 30 on which are swingably mounted the ratchet pawls 31 which operate the numbering wheels by engaging their ratchet teeth as the pawl swings in a counterclockwise direction after return of the main plunger 6 by 50 the spring 6' to its outwardly extended position from a depressed position. In present numbering devices the unit wheel 15 or the numbering wheel corresponding thereto is solid and when the numbering wheels have been brought into po- 55

sition to depress the characters thereof, and the unit wheel is positioned at zero, the other numbering wheels do not print, but the device continues to print the numbers of the unit wheel 5 from "1" to "9" until after reaching "9"; the further turning of the unit wheel causing the numeral "1" of the next wheel to be put in printing position. In this fashion, the unit wheel works the tens wheel, the tens wheel works the 10 hundredths wheel, etc. In accordance with the present invention, the unit wheel is altered so as to possess a manually depressible character 14 in the same mechanical arrangement as the depressible characters of the other numbering wheels 15 and similarly engageable in the notch 13 of the shaft 12 in a depressed position, so that with the main plunger 6 locked at a printing level by the engagement of the dog 22 with the tooth 20 of the cheek piece, the aligned characters of all of the 20 numbering wheels, including the unit wheel 15, may be depressed below the printing level, so that the device prints only "No."

Although I have shown and described herein a preferred embodiment of my invention, it is 25 to be definitely understood that I do not desire to limit the application of the invention thereto, and any change or changes may be made in the structure and arrangement of the parts, within

the spirit of the invention and the scope of the subjoined claim.

Having described the invention, what is claimed as new is:

In a numbering machine which has a plurality 5 of numbering wheels including a unit numbering wheel operatively related to the other numbering wheels, a swinging pawl in operative relation to said unit wheel with means operably interconnecting the said other numbering wheels for successive operation as a result of operation of the unit numbering wheel by said pawl, a main numbering plunger operatively connected with said pawl and adapted to be operated by engagement with the work, a manually depressible character 15 in said unit numbering wheel, and a manually positioned dog normally disengaged from a part of the said pawl and leaving the machine in normal operating position, said dog being engageable with a part of said pawl to hold said pawl 20 in a position retaining said main plunger in an indrawn position with its character projecting only to printing level, whereby said machine prints only the character on the main plunger and said pawl fails to operate the numbering 25 wheels.

JOHN GORRELL.
